UNITED STATES PATENT OFFICE.

BART M. BARRICKMAN, OF PORTLAND, OREGON.

CLOTHESPIN.

1,344,254.

Specification of Letters Patent. Patented June 22, 1920.

Application filed November 23, 1918. Serial No. 263,845.

To all whom it may concern:

Be it known that I, BART M. BARRICKMAN, a citizen of the United States, residing at Portland, in the county of Multnomah, State of Oregon, have invented certain new and useful Improvements in Clothespins; and I do hereby declare the following to be a full, clear, and exact description of the invention, such as will enable others skilled in the art to which it appertains to make and use the same.

The present invention relates to new and useful improvements in wire clothes pins, more particularly of that type formed of a single length of wire bent to provide a pair of jaws resiliently opposed to relative movement whereby to exert a proper gripping action on articles inserted therebetween.

It is in general the object of the present invention to simplify and otherwise improve the structure and to increase the efficiency of devices of this character.

A more detailed object is to provide an improved gripping action of the clothes pin both with respect to the range of resilient action afforded the jaws and with respect to a balanced gripping relation of the various jaw portions.

With the above and other objects and advantages in view, the invention resides, more particularly in the novel combination, formation and arrangement of parts herein-after described and particularly pointed out in the appended claims.

In the accompanying drawings:

Figure 1 is a perspective view of the improved clothes pin.

Fig. 2 is an edge elevational view thereof.

Fig. 3 is a front elevational view thereof.

Fig. 4 is a sectional view therethrough.

Referring now more particularly to the accompanying drawings, a single length of wire from which the pin is formed is bent centrally and the portions adjacent the bend extend in contiguous relation to form a pair of jaw shanks 5, the central bend 6 of the wire being disposed at the outer ends of the jaw shanks, and the inner ends of the jaw shanks are twisted together at 7. From the twisted portions 7, each stretch of wire is coiled outwardly in a helical spring at 8, the jaw shanks 5 being disposed tangential to the helix, and from the outer ends of the coils the wire is extended tangentially in substantially the plane of the shanks 5 to form a pair of jaw shanks 9, these jaw

shanks being parallel and spaced laterally at opposite sides of the pair of jaw shanks 5. The free end portion of one of the shanks 9 is turned laterally at right angles 60 as shown at 11 and is terminally connected to the extremity of the other shank 9 as shown at 12. The pair of shanks 5 which jointly form one of the gripping jaws of the clothes pin are provided with a pair of bends 13 and 13' directed forward from the plane of the shanks 9 which latter shanks form jointly the other gripping jaw of the clothes pin. It will be noted that the bend 13 is of less amplitude than 70 that of the bend 13'. The shanks 9 are provided also with bends 14 and 14' directed rearwardly, or oppositely to the alined bends 13 and 13' with which they correspond in position and amplitude 75 respectively. These coöperatively disposed bends are the portions of the jaws that directly engage the article to be held to the clothes pin, it being understood that when the line is of small diameter, the upper and 80 minor bends are active and when the diameter is greater, the lower or major ends are active. The free end portions of the gripping jaws, it will be noted, are diverged to their extremities to facilitate engagement 85 of the pin with the clothes line.

An exceedingly simple, readily formed and durable clothes pin has thus been provided which possesses a wide range of resilient action and which may be most readily 90 applied in operative position to a clothes line. The gripping action of the jaw shanks 5 is exerted between the jaw shanks 9, and thus an entirely balanced gripping action is 95 procured.

It is noted that the jaw shanks 9 are longer than the jaw shanks 5, and thus should the resilience of the jaws in a normal operation become lessened by continued use or unusual strain, the jaw shanks 5 may 100 be passed between the shanks 9, to lie at the other side of them when articles may be gripped between the other faces of the jaws and the reentrant bends between 13 and 13' and between 14 and 14' become effective. 105

For securing the pin permanently to a clothes line, a link 15 is provided, having an eye 16 at one end loosely engaging the outer convolutions of one of the coils 8 and having a normally closed spring hook 17 110 at its other end for engagement on the clothes line.

I am aware that clothes pins have heretofore been formed of a single length of wire bent to provide a pair of resiliently opposed jaw portions, and my invention therefore 5 resides in the particular formation recited in the claims to procure a most simple, readily manufactured and efficient clothes pin of this type.

What is claimed is:

- 10 1. A clothes pin comprising a single length of wire having its ends connected, the wire being extended from said connecting ends to form a pair of spaced jaw shanks, then coiled, and then extended from its coiled portion to form a second pair of 15 jaw shanks shorter than and capable of swinging through the first, the jaws having bends facing each other when the shorter jaw is on either side of the longer.
- 15 2. A clothes pin comprising a single length of wire having its ends connected, the wire being extended from said connected ends to form a pair of jaw shanks, and then coiled and extended from its 20 coiled portion to form a coacting second 25

pair of jaw shanks, said second pair of shanks being twisted together adjacent the coiled portion.

3. A clothes pin comprising a single length of wire having its ends connected, 30 the wire strands being extended from said connected ends in spaced parallel shanks, then coiled inwardly from said shanks, then twisted together, and finally extended to form a coacting second pair of jaw shanks 35 shorter than the first.

4. A clothes pin comprising resiliently connected jaws, one of which includes spaced shanks terminally connected and of greater length than the other jaw for movement of the latter jaw between them for co-operation with their opposite faces selectively.

In testimony whereof, I affix my signature, in the presence of two witnesses.

BART M. BARRICKMAN.
